OIL BURNING STOVE

Arthur T. Cole and Hugh L. Cole, Chicago, Ill.

Application February 14, 1931. Serial No. 515,709

4 Claims. (Cl. 126—93)

This invention relates to improvements in stoves and more particularly to oil burning stoves.

It is an object of this invention to provide an efficient and yet inexpensive stove of this character so constructed as to burn any kind of liquid fuel and produce a high degree of combustion.

The accompanying drawings illustrate a preferred form of this invention with the understanding that minor detail changes may be made without departing from the scope thereof.

Figure 1 is a vertical central sectional view of an embodiment of this invention;

Figure 2 is a top plan view of Figure 1; and Figure 3 is a view in section taken on the line 3—3 of Figure 1, with parts broken away.

In carrying out this invention as here shown a circular sheet metal casing 1 is provided which is closed at the bottom and provided with a removable cast top 2 provided with a flue opening 3 adapted to be connected by stove piping to a chimney or the outside atmosphere. The top 2 is also provided with a central opening and means for attaching a vertical blast pipe 4 to communicate with said central opening. The upper surface of the top surrounding the central opening is formed to mount a movable closure 5 adapted to regulate the size of the passageway communicating with the pipe 4.

30 A short distance above the closed bottom of the casing 1 a removable fuel receiving and burning bowl 6 is supported upon an annular bracket 7 secured to the inner side wall of the casing 1. The periphery of the bowl 6 is preferably provided with a horizontal flange 8 adapted to rest in a similarly shaped recess upon the annular bracket 7. The bowl 6 is preferably shallow, that is if the inner diameter is ten inches its depth is approximately three inches. The center of the bottom of the bowl 6 is provided with curved conical projection 9 with a diameter at the base of the cone about equal to the depth of the bowl and extending upward about one third of the depth of the bowl. As clearly shown in the drawings the apex of the conical projection 9 is somewhat flattened for a purpose presently described.

50 The blast pipe 4 carried upon the top 2 is concentric with the conical projection 9. It is desirable to construct the blast pipe of a diameter about equal to the radius of the base of the conical projection 9 and terminate the discharge of the blast pipe or its continuation as presently described approximately one fifth of its diameter above the surface of the cone 9, thus causing the

discharge end of the blast pipe to extend into the bowl 6 to be below the periphery of the bowl, as is clearly shown in the drawings. To maintain this relation it is preferable to provide a tubular chair 10 providing a continuation of the blast pipe 4 and having spaced apart legs 11 adapted to rest upon the sides of the cone 9, the inner diameter of which chair equals that of the blast pipe 4 and the upper walls of which are recessed to receive the end of the blast pipe, as shown.

55 A liquid fuel tank 12 is supported in any desired manner upon the exterior of the stove and is provided with an oil pipe 13 to discharge the liquid fuel from the apex of the cone 9, as through the portion 13b of the oil pipe 13 which passes through the conical projection 9 and terminates at the apex thereof, the flow of which fuel is regulated in any manner desired, such as by a float valve mechanism indicated at 13a, to produce a constant rate of discharge at the apex 70 of the cone 9 from which the fuel flows or spreads 75 equally passing over the curved surface to the sides of the bowl 6. The somewhat flattened curved apex of the projection 9 promotes a gradual spread of the oil which permits the air from the blast pipe 4 to mingle intimately therewith. A cock or valve is interposed in the fuel line, if not combined with the float valve, to initiate and stop the flow of the liquid fuel.

80 The natural draft from the chimney or atmosphere sets up through the flue opening 3 an air exhausting effect upon the interior of the casing 1 above the bowl 6 and therefore sets up a down draft through the blast pipe 4. This draft is employed to furnish primary air for combustion of the liquid fuel when the stove is operating. It is preferable to provide a plurality of horizontal air passages 14 through the wall of the bowl opening just under the flange 8, the axes of which are tangential to an annular region vertically above the base of the cone 9 and extend in the same general plane. These air passages are desirably above the discharge end of the blast pipe as shown. The space between the bottom closure 15 of the casing 1 and the underside of the bowl 6 is provided with an opening 15 leading to the atmosphere, preferably provided with a movable closure 16, whereby the natural draft through the flue opening 3 not only sets up a down draft 90 through the blast pipe 4 but also draws air from the atmosphere through the bottom opening 15 into the space below the bowl 6 and from thence through tangential passageways 14 adjacent the upper edge of the bowl with a swirling movement 100 105 110

into the interior of the casing 1. The air thus drawn into the interior of the stove from below the bowl is employed as secondary air for the combustion of the fuel when the stove is operating. 5 By the proper manipulation of the closures 5 and 16 the proportion of the primary and secondary air is regulated in accordance with the character of the fuel employed.

In operating this stove, the fuel line valve is 10 opened allowing the fuel to spread over the cone 9 and a match, piece of burning paper or other means of ignition is applied through the door 17 of the top 2. The fuel will burn with a smoky flame as insufficient air for complete combustion 15 is supplied through the blast pipe 4. The draft down pipe 4 impinging upon the cone 9 will cause the flame to spread to the outer edge of the bowl 6 where it comes in contact with the secondary air issuing with a swirling motion from the passages 14 causing a mixture of the secondary air with the gases from the incomplete combustion 20 of the fuel, unite therewith and form complete combustion so that the flame becomes yellow or 25 luminous and fills the lower portion of the casing 1 above the bowl 6.

The heat from the flame, as the stove operates, not only heats the pipe 4 so that the air issuing from below the chair 10 impinges upon the film of the liquid fuel upon the top of the cone 9 as a 30 hot blast of approximately nine hundred degrees Fahr., but also the heat of the flame is transmitted through the wall of the bowl 6 to the space therebelow, whereby the secondary air entering through opening 15 is pre-heated before 35 it mixes with the gases of incomplete combustion. The heat at the cone 9 is so great that any carbon that may be collected thereon is immediately oxidized by the hot blast from the pipe 4.

A stove of this construction when started immediately begins normal operation and radiates heat. If desired a spaced apart shell 18 may be supported about the exterior of the casing 1, as shown, to set up a more violent circulation of air 40 adjacent the stove.

45 What I claim is:

1. A liquid burning stove including a closed casing, a bowl having a concentric cone of a basic diameter substantially equalizing the depth of the bowl and a curved apex projecting upward from the bottom thereof substantially one-third of the distance to the top of the bowl, means for supplying liquid to the center of the curved apex of said cone, a flue passage provided in the top closure of the casing, a draft pipe 50 arranged concentric with the said bowl cone of a diameter substantially equaling the radius of said cone base opening through the top closure and terminating substantially at one-fifth of its diameter from the curved top of the said cone, means supporting the bowl spaced apart from the bottom closure, said draft pipe supplying primary air for initiating combustion of the liquid fuel, and means for supplying secondary air to complete the combustion of the fuel from the underside of the bowl and including the provision 55 of air passages in the wall of the bowl adjacent the top thereof and directed tangentially to an annular region vertically above the base of the cone, and an air passage in the casing below the bowl.

70 2. A liquid burning stove including a closed casing, a bowl having a concentric cone of a basic diameter substantially equaling the depth of the bowl and a curved apex projecting upward from

the bottom thereof substantially one-third of the distance to the top of the bowl, means for supplying liquid to the apex of said cone including a fuel supply pipe leading from below and opening through the center of the curved apex of the cone and having means for regulating the flow of liquid fuel therethrough, a flue passage provided in the top closure of the casing, a draft pipe of a diameter substantially equaling the radius of said cone base arranged concentric with the said bowl cone opening through the top closure and terminating at substantially one-fifth of its diameter from the curved apex of said cone, means for maintaining a constant spaced apart relation between the bottom of the draft pipe and top of the cone including a chair having a concentric passage therethrough of equal diameter to the draft pipe and an opening held at a distance equaling substantially one-fifth of its diameter from the upper surface of the curved apex by spaced apart legs resting upon said curved surfaces, means supporting the bowl spaced apart from the bottom closure, said draft pipe supplying primary air for initiating combustion of the liquid fuel, and means for supplying secondary air to complete the combustion of the fuel from the underside of the bowl and including the provision of air passages in the bowl adjacent the top thereof and directed tangentially to an annular region vertically above the base of the cone and an air passage in the casing below the bowl.

3. In a liquid fuel burning stove, the combination including a shallow bowl; a curved conical projection centrally disposed within said bowl, 110 said projection having a somewhat flattened apex terminating a relatively short distance above the bottom of the bowl and well below its rim; a fuel discharge conduit passing through said projection and terminating at said apex; a blast pipe 115 supported centrally of said bowl, said pipe terminating at its lower end within said bowl below its rim and a relatively short distance above said apex; and passages in said bowl spaced about its periphery below said rim but above the lower 120 end of the blast pipe.

4. A liquid fuel burning stove including a cylindrical casing; an internal annular bracket in said casing intermediately thereof; a shallow bowl in said casing having at its rim an outwardly extending annular flange supported on said bracket; a curved conical projection centrally disposed in said bowl, said projection having a somewhat flattened apex terminating a relatively short distance above the bottom of the 130 bowl and well below its rim; a fuel discharge conduit passing through said projection and terminating at said apex; a blast pipe supported centrally of said casing above said bowl, said pipe terminating at its lower end within said 135 bowl below its rim and slightly spaced from the apex of said projection; an adjustable closure for said pipe communicating with the exterior of the casing; another adjustable closure in said casing communicating with the exterior thereof 140 and with the space below the said bowl; and air passages in said bowl spaced about its periphery below said flange but above the lower end of the blast pipe, said air passages directed tangentially to an annular region vertically above 145 the base of the cone.
